[57] CLAIM

The ornamental design for a keyboard cover and copy holder, as shown and described.

DESCRIPTION

FIG. 1 is a perspective view of a keyboard cover and copy holder showing my new design;

FIG. 2 is a right side elevation view, the left side elevation view being a mirror image thereof;

FIG. 3 is a front elevation view thereof;

FIG. 4 is a rear elevation view thereof;

FIG. 5 is a top view thereof;

FIG. 6 is a bottom view thereof; and,

FIG. 7 is a perspective view, showing the keyboard cover and copy holder in an open configuration.
